PRINTER CABINET

Clayton Harold Clark, Mundelein, Ill., and Gerald M. Adams, Fayetteville, N.Y., assignors to SCM Corporation, New York, N.Y., a corporation of New York

Filed May 16, 1968, Ser. No. 11,968

Term of patent 14 years

Int. Cl. D14—02

U.S. Cl. D64—11

Fig. 1

Fig. 2

Fig. 3

Fig. 4

Fig. 5

FIGURE 1 is a perspective view of a printer cabinet or the like, showing our new design;

FIGURE 2 is a top plan view of the printer cabinet shown in FIGURE 1;

FIGURE 3 is a rear elevational view of the printer cabinet shown in FIGURES 1 and 2;

FIGURE 4 is a left-side elevational view of the printer cabinet as viewed in FIGURE 1; and

FIGURE 5 is a front elevational view of the printer cabinet.

The essential features of our design reside in the portions shown in solid lines, conventional elements being shown in broken lines.

We claim:

The ornamental design for a printer cabinet or the like, substantially as shown and described.
